UNITED STATES PATENT OFFICE.

GRANVILLE A. HUMASON, OF SHREVEPORT, LOUISIANA, ASSIGNOR, BY MESNE ASSIGNMENTS, TO C. E. REED, OF HOUSTON, TEXAS.

DRILL-BIT.

1,294,106.

Specification of Letters Patent. Patented Feb. 11, 1919.

Application filed February 10, 1918. Serial No. 747,461.

To all whom it may concern:

Be it known that I, GRANVILLE A. HUMASON, a citizen of the United States, residing at Shreveport, in the county of Caddo and 5 State of Louisiana, have invented new and useful Drill-Bits, of which the following is a specification.

This invention relates to bits for use in drilling rock, one of the objects of the invention being to provide a bit having cutting elements of novel form which are mounted for movement relative to the bit and which have means whereby a lubricant can be supplied continuously to them so as 10 to enable them to rotate freely at all times during the operation of the bit.

A further object is to provide means for supplying water to the bit during the operation thereof.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings:—

Figure 1 is a view partly in elevation and 25 partly in section of the bit.

Fig. 2 is a similar view taken at right angles to Fig. 1.

Fig. 3 is a view of the face or active end of the bit.

Fig. 4 is a plan view of the bit.

Fig. 5 is a side elevation of a modified form of cutter.

Fig. 6 is a section on line A—B Fig. 5.

Fig. 7 is a detail view of a portion of the 45 bit and showing a modified form of cutting disk.

Referring to the figures by characters of reference 1 designates a substantially conical head having an externally screw threaded extension 2 at one end adapted to engage the drill actuating rod or other element employed. The other or large end of the head 1 has a cylindrical extension 3 provided, at

diametrically opposed points, with channels 4 converging upwardly. A substantially 55 semi-cylindrical recess or socket 5 is formed in the extension 3 between the channels 4. Extending diametrically within the cylindrical portion 3 and longitudinally of the recess or socket 5 is a tubular bearing member 6 on which a series of cutting disks 7 is arranged. Each of these cutting disks is provided, in one side, with a circular recess 8 while its other side has a boss or extension 9. The boss on each disk projects into the 60 recess in the next adjoining bit so that grit, etc., is thus prevented from working between the disks and onto the bearing member 6. The peripheries of the disks 7 can be provided with V-shaped teeth extending 65 throughout the width of the disk and intersected at their centers by an annular V-shaped groove 10. This construction has been shown in Figs. 1, 2 and 3. If preferred, however, the disks can be provided 70 with peripheral grooves 11 extending transversely of the disks, as shown in Figs. 5 and 6, thus forming cutters between the grooves. Obviously cutters of other forms can be used in lieu of the one shown and described. 75

Extending across the grooves or recesses 4 and perpendicular to the walls thereof, are bearing pins 12. These pins may be secured in position in any preferred manner. In the structure shown in Fig. 1, the pin 12 has 80 a threaded nipple 13 at one end while its other end has a threaded head 14, the nipple being seated within a recess 15 formed at the inner end of a bore 16 while the head 14 is screwed into a counter bore 17 arranged 85 at the outer end of bore 16. Each of the bearing pins 12 has an axial passage 18 one end of which is preferably closed by means of a screw plug 19. A cutting disk 20 is mounted for rotation on each pin 12 and, as 90 shown in the drawings, this disk is preferably provided with V-shaped teeth 21 extending transversely of the periphery. Furthermore, as shown in Figs. 1 and 3, the disk 20 can be frusto-conical so that the 95 lower or active teeth will thus be extended at right angles to the longitudinal axis of the head 1. This construction is not essential, however, as if desired, each of the cutting disks can be substantially cylindrical 100 with the active edges of its teeth parallel

with the axis of rotation of the disk. This form of cylindrical disk has been illustrated at 22 in Fig. 7.

- The tubular bearing member 6 has a series 5 of outlet openings 23 in the lower portion thereof, one of these openings being within each of the disks 7 and constituting means for directing a lubricant from the bearing member 6 to the inner surface of the disk. 10 One end of the bearing member 6 can be provided with a screw plug 24 or the like whereby access may be had conveniently to the interior of the bearing member for the purpose of cleaning it. The bearing member 15 can be secured in place within the cylindrical member 3 of the head 1 in any suitable manner, as by providing it with a threaded nipple 25 projecting into one end wall of the recess or socket 5. 20 Formed longitudinally within the head 1 is a bore 26 constituting a portion of a lubricant container, there being a tubular receptacle 27 secured to the head and extending upwardly therefrom, this receptacle 25 opening into the bore 26 and being likewise designed to hold a lubricant. Extending from the lower end of the bore 26 are ducts 28, one of these ducts being constantly in communication with an opening 29 in the upper 30 portion of the bearing member 6 while the other ducts 28 are constantly in communication with the inlets 30 of the passages 18 in bearing pins 12. An outlet opening 31 extends from each passage 18 and lubricant is 35 adapted to flow through these passages to the bearing faces of the pins 12 and disks 20. Thus it will be seen that when the bore 26 and receptacle 27 are partly or entirely filled with a lubricant, said lubricant will 40 gravitate along the ducts 28 to the interiors of the bearing members 6 and 12 from which the lubricant will be distributed to the bearing faces of the disks 7 and 20 and to the outer surfaces of the members on which the 45 disks are mounted. The disks are therefore kept constantly lubricated and, during the actuation of the bit, will be gradually rotated. The disks 20 are extended slightly beyond the periphery of the cylindrical extension 3 and therefore serve to cut an opening slightly greater in diameter than the diameter of said extension 3, thus permitting the bit to be raised and lowered freely.

For the purpose of keeping the disks constantly supplied with water, a series of water conduits or ducts 32 are formed within the head 1 and open into the tubular rod 33 to which the head 1 is connected. These ducts also extend downwardly and two of the 60 ducts discharge into the grooves or recesses 4 while the remaining duct discharges into the recess or socket 5. Thus it will be seen that streams of water will be discharged constantly upon the disks during the operation of the bit.

Importance is attached to the fact that the head of the bit is formed in a single piece and there is thus no danger of the head contracting or expanding to an undesirable extent while in use.

By referring particularly to Fig. 3 it will be seen that the central cutting disks 7 project into the path of the side cutting disks 20 so that the formation of a core or any other upstanding portion in the path of the 75 head is positively prevented.

What is claimed is:

1. A rotary drilling tool for use in boring deep oil wells comprising a head having at the upper portion thereof means for attachment to a drill stem, or rod, having in its lower portion a recess opening out through the bottom thereof, and having a pocket in its lower portion on each side of said recess, a plurality of cutters mounted to rotate in said recess, a single rotary cutter mounted in each pocket, means for lubricating said cutters and means for directing a flushing fluid from the drill stem through the head and into said pockets upon the cutters located within the same, substantially as described.

2. A drill bit including a head, a cutter supporting bearing, revoluble cutters on said bearing extending diametrically across the center of one end of the head, and side cutters revoluble in planes converging into the head, all but the active portions of all the cutters being housed in the head.

3. A drill bit including a head, a cutter supporting bearing, revoluble cutters thereon extending continuously across the center of one end of the head, and side cutters revoluble in planes converging into the head, all but the active portions of all the cutters being housed in the head.

4. A drill bit including a head, side cutters revoluble in planes converging into the head, and a series of closely lying revoluble cutters extending continuously across the center of one end of the head and into the path of the side cutters, all but the active portions of all the cutters being housed in the head.

5. A drill bit including a head having recesses in one end, a bearing member extending within one of the recesses and across the center of said end, said bearing member being mounted at its ends in the head, revoluble cutting elements mounted on the 120 bearing member, and upwardly converging side cutting elements in the other recesses, all of said cutting elements being housed within the head except at their active portions.

6. A drill bit including a head having diametrically opposed obliquely disposed grooves in one end, and a recess centrally disposed in said end and between the grooves, a bearing member arranged axially 130

within the recess and diametrically within the head, bearing pins extending across the grooves, closely lying revoluble cutting devices mounted upon said bearing member 5 and extending across the center of the head, and cutting elements upon the pins and projecting beyond the end of the head.

In testimony that I claim the foregoing as my own, I have hereto affixed my signature in the presence of two witnesses.

GRANVILLE A. HUMASON.
